UNITED STATES PATENT OFFICE.

DAVID YULEE READ, OF WASHINGTON, DISTRICT OF COLUMBIA, ASSIGNOR TO
ELLIOTT-FISHER COMPANY, A CORPORATION OF DELAWARE.

PLATEN EQUIPMENT.

Application filed April 30, 1923. Serial No. 635,659.

To all whom it may concern:

Be it known that DAVID Y. READ, a citizen of the United States, residing at Washington, District of Columbia, has invented 5 certain new and useful Improvements in Platen Equipments, of which the following is a specification, reference being had therein to the accompanying drawing.

This invention relates to platen equipment, 10 and more particularly to equipment for machines of the flat platen type.

The object of the invention is to facilitate statement and ledger posting in which it is desired that the items shall appear in a vertical column on the statement, while the record of the items will appear in a horizontal line on the ledger, the records of successive statements appearing on successive lines of the ledger.

20 To the accomplishment of the above object, the invention resides in equipping the platen with paper holding and feeding means, which, while retaining the ledger sheet stationary retains the statement sheet in proper position over the ledger during the printing of an item and advances the statement sheet both transversely and longitudinally of the platen to the next column position of the ledger sheet, so that when the 25 next item is printed below the first item on the statement sheet the record thereof will appear by the side of the first item record in the next column of the ledger sheet.

To the accomplishment of the object 30 stated and others subordinate thereto, the preferred embodiment of the invention resides in the construction illustrated in the accompanying drawings and hereinafter fully described.

40 In said drawings:

Fig. 1 is a plan view of the flat platen of the Elliott-Fisher billing machine of commerce.

Fig. 2 is a section on the line 2—2, Fig. 1.

45 Fig. 3 is a detail perspective view, partly broken away, of the statement slide and guide.

Machines of the type under consideration 50 include a flat platen 1 mounted in a platen frame 2 surmounted by traveling printing mechanism not shown which travels longitudinally of the platen for line spacing and transversely of the platen for letter spacing. This permits the printing or typewriting of

words and numbers at any desired points of 55 work sheets mounted on the platen. Usually the platen 1 is movable vertically to clamp a work sheet as, for instance, a ledger sheet 3 against the under side of a work holding flange 4 which extends along one of the 60 side members of the frame 2. The ledger sheet is customarily printed with writing and column lines 5 and 6 dividing its surface into writing spaces and columns.

Imposed upon the ledger sheet in one 65 form of condensed billing is a bill or statement 7 on which certain data as, for instance, the items of a public service account are printed in a vertical column. As these items are printed one below another the record thereof is transferred to the ledger sheet as, for instance, through the medium of the carbon sheet 8. The record items thus transferred do not appear on the ledger 70 sheet one under another as they do on the bill or statement, but appear side by side in a horizontal row along a single writing line of the ledger but in different column positions, the column designations of the ledger sheet corresponding to the line designations 75 of the bill or statement sheet. To secure this vertical arrangement of the items printed on the statement sheet and the horizontal arrangement of the record of these items on the ledger sheet, it is necessary to move the statement sheet after each item entry, to the next 80 column position of the ledger sheet and also in a vertical direction to advance the next line of the statement sheet to bring it opposite the same line of the ledger sheet to which the previous entry was transferred. The sum of these two movements of the statement 85 is a movement corresponding to the diagonal of one column width of a line space, 90 and this diagonal when continued across the ledger sheet defines a line of advance for the statement sheet which is disposed at an angle of ten or fifteen degrees from the horizontal when the proportions are substantially as 95 shown.

100 This diagonal line of advance is defined by a guide 9 formed by the rear edge of a tapering guide plate 10 disposed transversely of the platen and having a row of stud apertures 11 at one end for the reception of the studs or pins 12 of a continuous feed tape 13. The tape 13 is a well known feature of machines of this type and is advanced as, for 105

instance, a line space at a time by any suitable means, such as a knurled wheel 14. This advance or adjustment of the tape 13 longitudinally of the platen feeds the guide plate 10 to successive line positions of the ledger, so that single line records of successive statements will appear on successive lines of the ledger.

Movable along the guide 9 is a bill or statement holder or slide 15 having a slideable connection with the rear edge of the guide plate 10 as, for instance, by the inter-folding of the adjacent edges of the plate 10 and the slide 15 as shown in 16 and 17 in Fig. 3. At its rear edge the slide 15 is provided with retaining means 18 which engages and holds the lower or front edge of the bill or statement. Retaining means 18 may be in the form of small projections located alternately in slightly different planes or staggered sufficiently to permit the reception and retention of the bill. To assist in the retention of the bill holder or slide 15 and to facilitate its accurate advance the distance of a column position after the entry of each item, slide advancing means is provided. This advancing means is in the form of a spring 19 having one end 20 secured to the slide 15 and its opposite end 21 free with the intermediate portion of the spring coiled or looped as indicated at 22. This intermediate coil or loop 22 causes the two ends of the spring to normally stand in separated relation as indicated by dotted lines in Fig. 1.

The free end 21 of the advancing spring is designed to engage projections 23 preferably struck up from the metal of a guide plate 10. The full line showing in Fig. 1 shows the parts in the positions they assume when the operator by squeezing the ends of the spring 19 together has advanced the statement until the end 20 of the spring has been arrested by a projection 23. If now the spring is released the free end 21 will move to the position indicated by dotted lines and engage the next projection 23. After the entry of an item the operator will again squeeze the advancing spring together causing the end 20 of the spring to move over the projection 23 originally engaged by it, and to advance until arrested by the next projection. The operator will again release the spring; the free end will advance to the next projection and after the entry of the next item on the statement, the feeding or advancing operation just described will be repeated. Obviously, as the slide is moved along the inclined guide the statement carried by the former will necessarily be advanced in the diagonal line already described as necessary to secure a horizontal record of vertically disposed entries on the bill.

When a bill has been made out the bill

holder is returned to its new position for the reception of a new bill and is advanced one line space of the ledger by a line space movement of the guide plate with the tape 13, which, as before stated, is given a line space movement through the medium of the knurled wheel 14, or other means.

It is thought that from the foregoing the construction, operation and advantages of the described platen equipment will be clearly understood, but I reserve the right to effect such modifications of the illustrated structure as may come fairly within the spirit of the invention.

What I claim is:

1. The combination with a platen, of means for retaining superposed work sheets opposite the platen, said retaining means permitting, and guiding said work sheets in relative movement in an angular direction with respect to the lines of writing.

2. The combination with a platen, of separate devices for holding superposed work sheets, one of said devices movable to different positions transversely of the platen in an angular direction with respect to the lines of writing.

3. The combination with a flat platen, of means for holding a ledger sheet thereon, an angular guide disposed across the platen and a bill or statement holder shiftable along said guide in an angular direction with respect to the lines of writing.

4. The combination with a flat platen, of means for holding a ledger sheet thereon, an angular guide disposed across the platen, a bill or statement holder shiftable along said guide in an angular direction with respect to the lines of writing and a movable mounting for the guide.

5. The combination with a platen, means for holding the ledger sheet thereon, a guide movable in a line spacing direction and disposed at an angle with respect to the lines of writing, and a bill holder shiftable along the guide.

6. The combination with a platen, of a guide disposed thereover, a bill holder movable along the guide, and means for advancing the bill holder.

7. The combination with a platen, of a bill holder, means for advancing the bill holder to successive line space positions, and means for guiding the bill holder for movement in the letter space direction but at an angle with respect to the lines of writing.

8. The combination with a platen, of means for retaining a ledger sheet thereon, a feed tape, an inclined guide extended from the feed tape, and a bill holder movable along said guide.

In testimony whereof I hereunto affix my signature.

DAVID YULEE READ.
